UNITED STATES PATENT OFFICE.

JOSEPH R. HERNDON, OF MARSHALL, TEXAS, ASSIGNOR OF ONE-EIGHTH
TO SAMUEL R. BURNETT, OF MARSHALL, TEXAS.

DRAFT OR BUFFING GEAR OR RIGGING FOR CARS.

SPECIFICATION forming part of Letters Patent No 787,445, dated April 18, 1905.

Application filed July 26, 1904. Serial No. 218,247.

To all whom it may concern:

Be it known that I, JOSEPH R. HERNDON, a citizen of the United States, residing at Marshall, in the county of Harrison and State of Texas, have invented certain new and useful Improvements in Draft or Buffing Gear or Rigging for Cars; and I do hereby declare the following to be a full, clear, and exact description of the invention, such as will enable others skilled in the art to which it appertains to make and use the same.

This invention relates to improvements in draft or buffing gear or rigging for cars.

The object of the invention is to construct a rigging of a minimum number of parts and economical and durable in construction.

Another object of the invention is to construct a rigging which is provided with reinforcing means adapted to be positioned within the keyways formed in the draft-timbers.

A still further object of the invention is to provide reinforcing means for the keyways, which are formed in the draft-timbers, and to improve the construction of the rigging, which is movably mounted between the draft-timbers.

With these and other objects in view the invention consists in certain novel constructions, combinations, and arrangements of parts, as will be hereinafter fully described, illustrated in the accompanying drawings, and more particularly pointed out in the claims hereto appended.

In the drawings, Figure 1 is a plan view of a mechanism constructed in accordance with the present invention. Fig. 2 is a plan view of another embodiment of the present invention. Fig. 3 is a vertical central sectional view of the mechanism, taken on lines A A, Fig. 1, showing the draw-bar removed therefrom. Fig. 4 is a plan view of the keyway-liner or housing member, which is adapted to be inserted into the elongated apertures formed in the draft-timbers, into which the cross keys or heads are inserted. Fig. 5 is an end view in elevation of the front cushioned follower. Fig. 6 is a reverse view of the construction of the follower depicted in Fig. 5. Fig. 7 is a view in side elevation of the front

of a follower employed in the construction of the mechanism. Fig. 8 is an end view of the member depicted in Fig. 4, the same being shown in its normal horizontal position.

In carrying out the present invention I have provided a pair of metallic keyway liners or irons 1, which are to be positioned within elongated apertures formed in the draft-timbers in combination with draft and buffing gear means which is positioned between the metallic members 1, secured to the draft-timbers.

The keyway liners or irons comprise in their construction an approximately flat body portion 2, which is provided with parallel flanges 3, extending longitudinally thereof. Said flanges 3 are constructed for the purpose of forming a guideway for cushioned followers, hereinafter described. The flanges 3 extend from the body portion 2 upon one side thereof, and integrally secured to and projecting from the opposite side of said body portion 2 is a plurality of housings 4. The housings 4 are approximately rectangular in construction and are of sufficient length to extend through the apertured portion of the draft-timbers 5 for the purpose of forming a metallic reinforced surface, which is adapted to be engaged by the cross keys or heads 6. The portions 4 of member 1 are positioned in elongated apertures, said portions 4 entirely filling the apertured portion of members 5, thereby retaining members 1 in an assembled position with draft-timbers 5, without employing bolts or any similar securing means. Each of the housings 4 is provided with integral webs 7, forming braces therefor, which are secured also to the body portion of member 1, said webs 7 being formed diametrically in opposite positions upon the housing 4. When the keyway-liners 1 have been properly positioned upon the draft-timbers 5, the flanged portions thereof will be extending toward the opposite member 1, thereby presenting two flanged metallic surfaces which are adapted to be engaged by the spring-followers and retain the same in an operative assembled position with the other elements employed in the draft-rigging mechanism. A stop 8 is formed

upon the follower-engaging face of the body portion 2 of member 1. I have shown in the accompanying drawings a plurality of apertures 9, formed upon the forward end of keyway-liner 1. Said apertures are constructed for the purpose of permitting of the passage of bolts 10 therethrough for assisting in positively retaining keyway liner or iron in position.

10 After the metallic reinforcing means for the elongated apertures which are formed in the draft-timbers has been positioned it will be necessary for the assembling of the other parts of the mechanism to position within the 15 housings formed upon the forward portion of member 1 a cross key or head 6, upon which is mounted a draw-bar 11. The draw-bar is provided with a suitable recessed portion 12, which is adapted to receive a boss 13, formed 20 upon the front or shank-engaging surface of a follower 14.

The cushioned follower 14 comprises in its construction an approximately rectangular body portion 15, which is adapted to be movably positioned within the flanged portion of the keyway-liners 1. Upon diametrically opposite portions of the body portion 15 there are formed semicircular extensions 16, which are provided with a plurality of parallel flanged integral portions 17, which are adapted to extend from portion 16 to the outer engaging face, upon which is integrally secured the hollow boss 13. A plurality of hollow bosses 18 are formed upon the inner or spring-engaging surface of member 14. The bosses 18 are constructed for the purpose of providing suitable means for positively retaining one end of each of the springs 19 in an assembled position therewith. The body portion 15 of follower 14 is provided with a plurality of cells 20.

The rear or auxiliary follower 21 is constructed similarly to the front or primary follower 14, except that upon its outer or engaging surface 22 there is not formed a boss similar to member 13. In this instance two of the parallel webs of reinforcing members 17 are extended at 23 to approximately a central point upon the surface 22, terminating in an oval slot or cut-out portion 24, into which one of the oval edges of member 6 is adapted to extend. It will be apparent that by means of the recessed web extensions 23 a positive lock is formed for the rear or auxiliary follower when it is in an assembled position with members 1 and rear cross-key 6, thereby preventing any oscillatory movement provided the guideways are worn sufficiently for permitting of the followers to be loosely mounted therein. The springs 19 19 are positioned upon the bosses 18, formed upon the front or primary follower subsequent to the positioning of said follower between the engaging faces of the keyway-liners after the forward cross-key 6 has been positioned within the

Referring to Fig. 2, the same principle of construction is employed as has been heretofore described for the construction depicted in Figs. 1 and 3. The essential difference between these constructions is that instead of employing wooden draft-timbers 5, 5, as in the described construction, I employ metallic draft-sills 5^a, which are provided with apertured portions 27, through which are passed securing means for retaining the sills 5^a to the central stringers of the car floor or frame. The construction and arrangement of the cross-keys 6, 6, link-coupling members 25, and draw-bar 11 in the embodiment depicted in Fig. 2 are similar to that depicted in Fig. 1. The construction of the primary follower 14^a and the auxiliary follower 21^a (shown in Fig. 2) is similar to that shown in the other figures of the drawings, except that in the embodiment Fig. 2 the followers 14^a and 21^a are positioned transversely and not vertically, as is the case of the preferred construction. The cushioning members 19^a are arranged in parallel transverse position upon followers 14^a and 21^a.

Each of Figs. 1 and 2 of the drawings depicts a complete draft-buffing mechanism for one end of each car, and it will be obvious that it will be necessary to position upon each car, near the ends thereof, a similarly-constructed mechanism when it is desired to couple the car with other cars. 110 115

The *modus operandi* is as follows: After the coupler which is secured to draw-bar 11 has been connected with an engaging coupler when outward pull or draft is made on member 11 motion is thereby imparted to the front cross-key or equalizing-pin 6, and subsequently movement is imparted to approximately parallel coupling-links 25 and thence to the rear equalizing-pin or cross-key 6. Owing to the construction of the elongated apertured portion of stringers 5 or metallic draft-sills 5^a the equalizing-pins or cross-keys 6 6 are permitted to have considerable play therein. When motion is imparted to rear cross-key, movement is imparted to the aux- 120 125 130

iliary follower 21 or 21^a, thereby compressing the flexible means which is interposed between the primary and auxiliary followers. The forward movement of rear cross-key 6 is continued until it is caused to engage the forward end portion of the housings 44 of members 1, and after this positioning has been obtained the draft or drawing is exerted directly upon the reinforced surface of stringers 55 or sills 5^a. It will be obvious that by this construction when initial movement is imparted to draw-bar 11 pressure is exerted upon the cushioning means instead of directly upon a metallic rigid surface, as would be the case if the cushioning means and its followers were obviated from the construction. If the members 25 were of such construction as to extend the entire length of the cars, thereby permitting of the same to be mounted upon each end of equalizing pins or keys 66 of each complete mechanism, the drawing upon one of the shanks 11 would, through the coupling-links 25, also cause movement of the cushioning means arranged in the mechanism secured upon the opposite end of the car. When the shank 11 is forced inward, the primary follower 14^a will compress cushioning means 19 and 19^a.

It will be apparent from the foregoing description that I have provided a peculiar-constructed mechanism which produces a draft-rigging to which is assembled a draw-bar or at certain times a buffer-rigging for the draw-bar, such mechanism being advantageous for the purpose of preventing unnecessary wear upon the assembling means for the draw-bar with the draft timbers or sills, whether the drawing or draft is exerted upon draw-bar 11 or an inward pressure, as the bumping of an adjacent coupler mounted upon another car, is the cause of movement of the mechanism.

While I have described in the foregoing description the preferred embodiments of the present invention and have depicted the same in the accompanying drawings, it will be apparent that certain alterations, modifications, and changes may be made in constructing mechanisms according thereto, and I reserve the right to make such alterations, modifications, and changes as shall fairly fall within the scope and spirit of the claims.

Having thus fully described my invention, what I claim as new, and desire to secure by Letters Patent, is—

55. 1. A device of the character described, comprising a plurality of keyway-liners, each keyway-liner comprising a body portion having a guideway formed upon one side and a plurality of housings formed upon the opposite side of said body portion, a plurality of followers movably mounted within said guideway, cushioning means interposed between said followers, a draw-bar assembled with said followers, and means connecting said draw-

2. In a device of the character described, the combination with a plurality of draft-timbers, each of said draft-timbers provided with a plurality of elongated apertures, of keyway-liners for each of said draft-timbers comprising a body portion having a plurality of flanges extending therefrom upon one side, a plurality of housings projecting from the opposite side of the same length as the width of said draft-timbers, said housings adapted to be positioned within the apertured portion of said draft-timbers, cushioning means positioned within the guideways formed by said flanges of the liners, and a draw-bar secured in an operative position with said cushioning means.

3. In a device of the character described, the combination with a plurality of draft-timbers, each of said draft-timbers provided with an aperture extending the entire width thereof, of a keyway-liner mounted within each of said apertured portions of said timbers, comprising a flanged body portion having an integral housing of the same width and diameter as said apertured portion of the draft-timbers, cushioning means movably mounted between said keyway-liners, and coupling-connecting means secured to said cushioning means.

4. In a device of the character described, the combination of a plurality of flanged members forming guideways, a primary and secondary follower slidably mounted within said guideways, each of said followers comprising a so-called body portion provided with projections extending from their inner and outer faces, cushioning means positioned upon the projections formed upon the inner faces thereof, connecting means engaging the outer faces of said followers, and a draw-bar, or the like, connected with said follower-connecting means.

5. In a device of the character described, the combination with a pair of flanged members, said flanged members providing a guideway, of a plurality of followers positioned within said guideway, each of said followers comprising an approximately rectangular celled body portion, a plurality of parallel bosses secured upon the inner face thereof, projecting means formed upon the outer face of said followers; cushioning means mounted upon said bosses formed upon the inner face of said followers, cross-keys mounted upon said flanged members, connecting means for said cross-keys, one of said cross-keys normally in engagement with one of said followers, and a draw-bar mounted upon one of said cross-keys and normally in engagement with a follower.

6. In a device of the character described, the combination with a pair of draft-timbers having a pair of elongated apertures of the same width of said timber, a metallic liner secured upon each of said draft-timbers, said

metallic liner comprising a body portion having a plurality of flanges extending from one side thereof, a plurality of housings extending from the opposite side of said liner of the same dimensions as the apertured portion of said draft-timbers, said housings adapted to be positioned within said apertured portions, a stop formed upon the flanged portion of each of said liners and between said flanges, 5 cushioning means interposed between said followers, transverse means positioned within said housings, connecting means secured to said transverse means, and coupler-connecting means engaging one of said followers and mounted upon said transverse means.

7. In a device of the character described, the combination with a plurality of apertured draft-timbers, of metallic housings of the same width as said apertured portion positioned therein, movable cushioned means assembled with said housings, and a coupler assembled with said cushioned means.

8. In a device of the character described, the combination with timbers having transverse apertures, a metallic liner positioned upon each of said draft-timbers, said liners provided with integral housings mounted within said apertured portions thereof and extending the entire width of the same, followers positioned between said liners, cushioning means interposed between said followers, connecting means assembled with said followers and normally retaining a coupler in engagement therewith.

35 9. In a device of the character described, the combination of a plurality of keyway-liners secured in parallel position, each of said keyway-liners comprising an approximately flat body portion having a guideway formed upon one side thereof, a stop formed in said guideway, a plurality of housings formed upon the opposite side of said body portion comprising an approximately rectangular casing, a plurality of followers positioned within said guideways of the liners, cushioning means interposed between said followers, a plurality of transverse members positioned within said housings of the liners, connecting means for said transverse members, and a draw-bar mounted upon one of said transverse members normally in engagement with one of the followers.

10. In a device of the character described, the combination with a plurality of draft-timbers, each draft-timber having a transverse aperture formed therein, of a reinforced housing extending the entire width of said apertured portion and mounted therein, said housing provided with parallel flanges secured thereto, movable cushioning means assembled with said housing, a draw-bar connecting with said cushioning means, and means for limiting the movement of said cushioning means.

11. A mechanism of the class described,

comprising a pair of parallel members provided with inwardly-extending flanges and outwardly-projecting housings, a plurality of followers mounted between said parallel members and within said flanged portions, cushioning means positioned between said followers, a draw-bar connected with said followers, and means for retaining said draw-bar and followers in an operative, assembled position.

12. In combination, a plurality of metallic liners each comprising a body portion of substantially uniform thickness and having a continuous guideway formed in one side thereof from end to end, and a reinforced housing projecting laterally from the opposite sides of the body portion, a stop formed in the guideway of said liners, and cushioning means secured between the liners and normally retaining a draw-bar in an assembled position therewith.

13. In a device of the character described, the combination with parallel guiding means, of a primary and auxiliary follower assembled with said guiding means, said primary follower comprising a celled body portion and integral extensions projecting in diametrically opposite positions from the sides of said body portion, a plurality of bosses formed upon one side of said primary follower, a boss formed upon the opposite side of said follower, said auxiliary follower comprising a celled body portion, said body portion having a plurality of extensions formed upon the sides thereof and extending therefrom in diametrically opposite positions, integral bosses extending from one side of said auxiliary follower and a plurality of parallel extensions having recesses formed upon the opposite side of the same, a draw-bar assembled with and engaging the primary follower, and means connecting said draw-bar with the outer surface of the auxiliary follower.

14. In a device of the character described, the combination with parallel apertured draft-timbers, a metallic lining for each of the apertured portions of said draft-timbers and of the same width, cushioned means assembled with said draft-timbers, and coupling means secured to said cushioned means.

15. In a device of the character described, the combination with apertured draft-timbers, of housings of the same dimensions as the apertured portions of the timbers positioned therein, movable means positioned within said housings, and a draw-bar or the like connected to said movable means.

16. In a device of the character described, the combination with parallel draft-timbers having transverse apertures, of metallic means of the same dimension as said apertured portions of said timbers positioned therein, movable transverse means positioned within the apertured portion of said timbers, cushioned means assembled with said transverse means,

and a draw-bar or the like secured to said cushioned and transverse means.

17. In a device of the character described, the combination of a pair of parallel members having guide-grooves in their adjoining faces and extending from end to end thereof, each member having an integral stop formed in its grooved portion, cushioned means posi-

tioned between said members, and a draw-
rod connected to said cushioned means. ^{1c}

In testimony whereof I hereunto affix my
signature in presence of two witnesses.
